UNITED STATES PATENT OFFICE.

WILL F. CADY, OF HARRISON VALLEY, PENNSYLVANIA.

RAILROAD-SWITCH.

SPECIFICATION forming part of Letters Patent No. 794,081, dated July 4, 1905.

Application filed March 13, 1905. Serial No. 249,895.

To all whom it may concern:

Be it known that I, WILL F. CADY, a citizen of the United States, residing at Harrison Valley, in the county of Potter and State of Pennsylvania, have invented certain new and useful Improvements in Railroad-Switches; and I do declare the following to be a full, clear, and exact description of the invention, such as will enable others skilled in the art to which it app-
10 pertains to make and use the same.

My invention relates to improvements in railway-switches; and it consists in certain novel features of construction, combination, and arrangement of parts, as will be herein-
15 after more fully described.

The object of the invention is to provide a simple, inexpensive, and efficient device of this character by means of which frogs and guard-rails may be dispensed with, so that it
20 will be impossible for any object to become so tightly wedged between the rails as to derail the train or cause a wreck.

The above and other objects, which will appear as the nature of my invention is better
25 understood, are accomplished by means of the construction illustrated in the accompanying drawings, in which—

Figure 1 is a top plan view of a railroad-switch constructed in accordance with my in-
30 vention, the two positions of the switch points or rails being indicated in full and dotted lines. Fig. 2 is a vertical transverse sectional view taken on the line 2 2 in Fig. 1, and Fig. 3 is a detail longitudinal sectional view taken on the line 3 3 in Fig. 1.

Referring more particularly to the drawings, A A' denote the rails of the main track; B B', the rails of the side track; C C', the stationary switch-rails, which have at their ends
40 pairs of movable switch-rails D D' and E E'. The inner ends of the switch rails or points are loosely connected, as shown at 1, or in any other suitable manner to the ends of the stationary switch-rails C C', and the pair of
45 switch-rails D D', which are moved toward and from the main-track rails A A', are connected by two bars 2 and 3. The other pair of movable switch-rails E E' coact with the point 5, formed by the intersection of the

rails B and A', and are connected by two bars 50 6 and 7. The points of the rails E and E' are moved toward and from the point 5 by means of the diamond-shaped lever 8, which is pivoted at one of its ends, as at 9, upon one of the cross-ties which support the track-rails and 55 has its other end pivoted, as at 10, to the cross-bar 6. The pivot 9 is strengthened by a bracket-plate 11, which is secured upon an ad-
jacent cross-tie. The diamond-shaped lever 8 is operated by means of two links 12, which 60 have one of their ends connected to said lever and their opposite ends connected to the arms 13 of bell-crank levers 14, which are pivoted at their angle, as at 15, beneath the ends of a bracket-plate 16, which is secured upon one 65 of the cross-ties. The opposite ends 17 of the bell-crank levers 14 are pivotally connected to the cross-bar 3, which extends out-
wardly to one side of the track and is connected to a suitable operating-lever 18, pivoted upon 70 a stand 19. This operating-lever and switch may be of any well-known or preferred con-
struction.

When the parts of the device are in the po-
sition shown in full lines in Fig. 1 of the draw- 75 ings, the movable switch-rails D' and E' aline with the rails A' and E', so that the main track is open; but when the parts are shifted to the position shown in dotted lines in said figure by operating the lever 18 the rails D 80 and E aline with the rails A, C, and B, so as to open the side track. By means of this con-
struction it will be seen that all of the mov-
able switch-rails are moved simultaneously
and that I may dispense with the use of frogs 85 and guard-rails at the point 5. Owing to this
construction it will be also noted that it will
be impossible for any object to become wedged
between the rails, so as to cause the derailment
of a train, and hence a wreck. 90

From the foregoing description, taken in connection with the accompanying drawings, the construction and operation of the invention will be readily understood without re-
quiring a more extended explanation. 95

Various changes in the form, proportion,
and the minor details of construction may be
resorted to without departing from the prin-

2
ciple or sacrificing any of the advantages of this invention.

Having thus described my invention, what I claim as new, and desire to secure by Letters 5 Patent, is—

1. A railway-switch comprising converging stationary switch-rail members respectively in line with one rail of the main and one rail of the side track, a movable switch-point at 10 each end of each of the said stationary switch-rail members, a connecting-bar between the movable switch-points, at the diverging ends of the stationary switch-rail members, reversely-disposed bell-cranks connected to said 15 connecting-bar, means to operate said bar, the switch-points connected thereto and the bell-cranks, a bar connecting the movable switch-points at the converging ends of the said stationary switch-rail members, a pivoted element in the angle between the last-mentioned 20 movable switch-points, and links respectively connecting said pivoted element at points on

opposite sides of its pivot to the said bell-cranks.

2. The combination with a main track and 25 a side track, of stationary switch-rails, a pair of movable switch-rails at each end of said stationary switch-rail, bars connecting the rails of each of said pairs, a diamond-shaped lever pivotally connected to one of said bars, 30 bell-crank levers pivotally connected to the other of said bars, links connecting said bell-crank levers and said diamond-shaped levers, and means for moving one of said bars to simultaneously actuate the said pairs of switch- 35 rails.

In testimony whereof I have hereunto set my hand in presence of two subscribing witnesses.

WILL F. CADY.
